BAG CLOSING MACHINE

Marcel A. Nicolas, Buffalo, N. Y., assignor to Consolidated Packaging Machinery Corporation, Buffalo, N. Y., a corporation of New York

Application April 8, 1939, Serial No. 266,726

9 Claims. (Cl. 93—6)

The present invention relates to filled-bag closing devices and, more particularly, relates to an improved adhesive-applying means for use in such devices.

In the copending application Serial No. 150,907, filed June 29, 1937 by Luta L. Cundall, administratrix of the estate of Robert N. Cundall, deceased, there is disclosed a bag-closing device of one type to which the present invention may be adapted. For the purposes of illustration, the present application shows the invention applied to the device disclosed in said copending application. It is to be understood, however, that the present invention is not limited to application to the particular machine illustrated in said copending application but that the invention may be adapted for use in bag-closing devices of many types.

In the device disclosed in said copending application a filled bag, having the side walls of its unfilled mouth portion tucked inwardly and its front and rear walls collapsed upon the side walls, is conducted to a station in which the collapsed mouth is doubled upon itself. The bag is then conducted to a station in which the doubled mouth is folded down upon the top of the bag to form a closure. In this latter station adhesive is applied to the area of the bag top upon which the doubled mouth is to be folded. As shown in said copending application, the means for applying the adhesive may comprise a flat plate or a plate having ridges formed on its active surface and means to move the plate from a source of adhesive into contact with the bag top. There is also shown means for applying pressure to the plate and for drawing the plate under such pressure across the bag top for the application of adhesive. Since the plate therein shown is relatively inflexible difficulty has been encountered in securing application of an evenly distributed adhesive coating upon filled bags whose tops may be irregular or inclined to the horizontal especially when the material within the bag is of a relatively unyielding character. This difficulty has been particularly noticeable in the packaging of sugar. Bags containing sugar are ordinarily subjected to a vibratory settling operation prior to the closing operation and, if the upper surface of the settled sugar happens to be irregular or inclined, it cannot be leveled by the application of a reasonable amount of pressure.

Accordingly, it is an object of the present invention to provide an adhesive-applying mechanism which will uniformly distribute adhesive

over a predetermined area irrespective of irregularities or imperfections of level of the surface of such area.

It is a further object of this invention to provide adhesive-applying mechanism which will apply adhesive in uniformly distributed, relatively narrow stripes upon a predetermined area irrespective of irregularities or imperfections of level of the surface of such area.

Other and further objects of the invention will be set forth or will become apparent from a consideration of the following description taken in connection with the drawings accompanying and forming a part of this specification.

According to the present invention, the adhesive-applying plate, such as shown in said copending application, is replaced by a universally flexible, resilient plate adapted to conform itself to such irregularities as are likely to occur in the upper surface of filled bags. More specifically, the flexible plate may be made up of a plurality of relatively narrow, closely spaced fingers individually flexible throughout their lengths. These fingers are preferably resilient and so mounted as to normally be within a single plane. Their flexibility permits them to be individually displaced from such plane to accommodate any irregularities in a surface against which the fingers may be pressed.

Referring now to the drawings forming a part of this specification, there is shown a preferred but not necessarily the only form of the invention and showing one form of bag-closing machine to which the invention may be adapted.

In the drawings:

Fig. 1 is a partial sectional view of a bag-closing machine embodying the invention;

Fig. 2 is a plan view of an adhesive-applying device according to the present invention, this view being taken in a broken plane indicated by the lines 2—2 in Fig. 1;

Fig. 3 is a section along the lines 3—3 of Fig. 2;

Figs. 4 and 5 are fragmental views illustrating the function of the adhesive-applying device;

and

Figs. 6, 7 and 8 are progressive diagrammatic views illustrating the operation of a bag-closing machine embodying the present invention.

Similar characters of reference indicate similar parts throughout the several views.

Referring now to Fig. 1, there is shown the essential mechanism of a station in a bag-closing machine of the type disclosed and claimed in said copending application Serial No. 150,907, filed June 29, 1937 by Luta L. Cundall, adminis-

tratrix of the estate of Robert N. Cundall, deceased. Only sufficient details for the proper disclosure of the present invention are illustrated in said figure and reference is here made to said cPending application for further details.

A filled bag 10 is conducted through preliminary stations of the machine and to the station illustrated in Fig. 1 by a conveyor (not shown) which is preferably intermittently operable in timed relation to the operation of the machine whereby the bag may remain stationary during the operation of the station illustrated in Fig. 1. The preliminary stations may be utilized to effect collapsing of the bag mouth and, if preferred, folding of the mouth upon itself into the position illustrated in Fig. 6 in which the free end 11 is folded downwardly toward the base of the upwardly extending mouth 12. It will be understood that suitable preliminary settling and shaping operations may be performed if so desired.

The station shown in Fig. 1 comprises an adhesive-applying head indicated generally at 13, a folding member indicated generally at 14 and suitable mechanisms for the operation thereof.

The adhesive-applying head 13 is pivoted at 15 to the upper arm 16 of a bell crank lever pivoted at 17 to the machine frame. The lower arm 18 of the bell crank lever is pivotally connected as at 19 to a link 20 which carries a cam follower 21 and guide 22. The guide 22 rests upon a drive shaft 23 which is rotated in a clockwise direction by suitable power means, not shown. The drive shaft 23 carries a cam 24 of suitable outline to effect, through the follower 21 and linkage above described the rocking of the bell crank 16, 18 about its pivot 17. This rocking motion is utilized to reciprocate the adhesive-applying head 13 between the full line position in Fig. 1, in which the head is in operative relation to a bag, and the dotted line position 13' in Fig. 1 in which the adhesive-applying head is positioned for contact with an adhesive-supply roller 25 rotatable within a suitable supply vat 26.

The adhesive-applying head 13 is adapted for movement about its pivot 15 in order that the head may be pressed into contact with the bag 10 or with the supply roller 25. To this end a bell crank lever 27 is pivoted upon the pivot 17. One arm 28 of the bell crank lever 27 is connected by a link 29 with the head 13. The other arm 30 of the bell crank lever 27 carries a roller 31 adapted to follow a rotary cam 32 driven in timed relation with the remainder of the machine by suitable means, not shown. A contractile spring 33 is stretched between a suitable anchorage 34 on the main frame of the machine and a post 35 upon the arm 30 of bell crank lever 27. The spring 33 urges the lever 27 to rock in a clockwise direction and thus serves through the link 29 to draw the head 13 downwardly. The rotary cam 32 controls the rocking of lever 27 under the influence of spring 33 and suitable depressions, such as 36, will permit the spring 33 to depress the head 13 at proper intervals.

As shown in Fig. 1, the head 13 has been advanced into contact with the bag 10 and the follower 31 has dropped into the depression 36 whereby the head 13 is pressed downwardly upon the top of the bag. The forward edge of the adhesive-applying blade is positioned along the plane of the top of the bag contents and the upstanding mouth portion 12. This position of the

head 13 is maintained by a concentric portion of the cam 24. At this time the folding member 14 starts its movement across the bag to fold the mouth 11, 12 along the line established by the adhesive blade.

The folding member 14 comprises a guide channel 37 into which the doubled bag mouth 11, 12 is introduced when the bag moves to the station illustrated in Fig. 1, and a pressing plate 38 adapted to fold the bag mouth and to press the same into contact with the top of the bag. The body portion 39 of the member 14 carries adjacent its rear end a pair of oppositely disposed studs, one of which is shown at 40. The studs 40 ride in suitable guide channels, one of which is shown at 41, formed in the main frame of the machine. The member 14 is thus mounted for horizontal movement along the guides 41 as well as pivotal movement about the centers of studs 40. The member 14 carries a cross bar 42 adapted to contact the upper surface of a suitable abutment 43 so proportioned as to maintain the pressing plate 38 above the level of the top of the contents of the bag 10. The cross bar 42 presents an inclined lower surface which is adapted to slide off the end 44 of abutment 43 upon movement of the folding member 14 to the left as viewed in Fig. 1. The member 14 is thus permitted to rock about its pivots 40 to a position limited by contact of the body 39 thereof with the abutment 43. This rocking movement is sufficient to permit the pressing plate 38 to drop into contact with the top of the bag. A suitable expansive spring 45 may be arranged upon a telescopic link 46 pivoted between the main frame and the member 14 to insure downward movement of the folding member when the same is moved to the left as discussed above.

The folding member 14 is moved in suitable timed relation with the remainder of the machine by a cam 47 carried by the shaft 23. The cam 47 operates a guided follower 48 which is connected through a link 49, bell crank lever 50 and link 51 with a suitable projection 52 formed upon the member 14. Thus, upward movement of the follower 48 results in horizontal movement of the member 14 to the left as viewed in Fig. 1.

The mechanism above described is so timed that the member 14 starts its movement to the left while the adhesive-applying head remains in the position illustrated in Fig. 1.

Referring now to Figs. 6, 7 and 8, it will be seen that Fig. 6 illustrates a position wherein the head 13 is moving toward the bag 10. This position is followed by the position illustrated in Fig. 1. In Fig. 7 the member 14 has moved to the left and the cross bar 42 had dropped off of abutment 43 whereby the pressing plate 38 is permitted to contact the top of the bag. As the movement of member 14 continues between the positions illustrated in Figs. 7 and 8, the adhesive-applying head 13 is withdrawn across the bag top. It is preferred that the head 13 shall continue to press downwardly on the bag top during its movement thereacross in order that adhesive may be distributed in advance of the folding of the bag mouth 11, 12. At a proper time the cam 32 operates to raise the adhesive-applying head 13 which thereafter moves through the position illustrated in Fig. 8 to the dotted line position 13' illustrated in Fig. 1. The folding member 14 continues its progress across the bag top to complete the folding of the bag mouth and to press the same into contact with the adhesive deposited upon the bag top. The

final position of member 14 is illustrated in Fig. 8 and the member thereafter returns to the position illustrated in Fig. 1.

All of the above mechanism and the operation thereof is disclosed and claimed in said copending application Serial No. 150,907, filed June 29, 1937, by Luta L. Cundall, administratrix of the estate of Robert N. Cundall, deceased, and forms no part, per se, of the present invention except insofar as it enters in combination with the novel features which will now be described.

It will be apparent from a consideration of the structure so far described that the tightness and efficiency of the bag closure is dependent to a large degree upon a uniform and reliable distribution of adhesive to the bag top. According to the present invention the means which actually applies and distributes the adhesive has been especially devised to insure uniform and reliable distribution irrespective of irregularities of the surface of the bag to which adhesive is to be applied.

Referring particularly to Figs. 2 and 3, there is shown one form of adhesive-applying means embodying the desirable features of the present invention. As shown in said figures, the head 13 includes a cross bar or similar structural member 53. One end of this cross bar may conveniently serve for pivotal reception of the upper end of link 29 as shown in Fig. 1. To the cross bar 53 there may be secured as by suitable bolts 54 an adhesive-distributing member 55 embodying the present invention. As shown in Figs. 2 and 3, the member 55 may comprise a plurality of separate fingers 56 made of thin spring metal or other suitable flexible resilient material. For convenience in manufacture and assembly, it is preferred to form the member 55 as a plate of suitable material having slots 57 cut therein at closely spaced intervals to form the fingers 56 although it is to be understood that such fingers may be individually formed and mounted in any desirable manner.

The number and spacing of the adhesive-applying fingers 56 may be varied as desired. It has been found advantageous to provide a relatively great number of narrow fingers 56 separated by slots 57 narrower than the fingers in order that the adhesive may be applied in the form of a plurality of closely spaced, relatively narrow stripes. This particular arrangement not only contributes to uniformity of adhesive distribution but also results in the formation of a sealed bag closure which may be opened with a minimum of damage to the bag walls.

The outer or active ends of the fingers 56 may be bent downwardly and curved slightly as indicated at 58 in Fig. 3. Such shaping of the fingers has been found to facilitate the conformation thereof to irregular bag tops.

The cross bar 53 may also carry a plate 59 whose outer edge 60 terminates just above the outer ends of the fingers 56. The edge 60 of plate 59 serves to tuck the downward portion 11 of the bag mouth into the fold as indicated in Figs. 6 and 7. The outer extremities of the fingers 56 are preferably aligned in order that they may establish the fold line at the base of mouth 12 as discussed above.

The operation of the improved adhesive-distributing member 55 in connection with the machine herein illustrated will be readily understood. When the head 13 moves from the position 13' in Fig. 1 through the position in Fig. 6 and to the position of Fig. 7, the extremities of

5 fingers 56 will be positioned in the apex of the angle between the plane of the top of the bag contents and the upstanding portion 12 of the bag mouth. The edge 60 of plate 59 will engage the free end 11 of the bag mouth and move the same into the position shown in Fig. 7. Under control of cam 32, the spring 33 will serve to draw the fingers 56 downwardly to exert pressure upon the bag top and this pressure will continue as the fingers are moved across the bag top to apply adhesive thereto.

10 The action of the individually flexible fingers 56 upon irregular or inclined surfaces is illustrated in Figs. 4 and 5. In Fig. 4 certain of the fingers are shown in contact with relatively high spots in the top of a bag 110. Continued downward pressure upon the adhesive-applying head will result in flexing of these fingers to allow the remainder of the fingers to be pressed into contact with relatively low spots in the bag top. As the fingers are drawn across the bag top, they will adjust themselves for continuous individual engagement with the bag material and will thus serve to uniformly distribute adhesive thereover.

15 In Fig. 5 a bag 210 is illustrated wherein the top of the contents has assumed a position inclined relative to the horizontal. As illustrated in this figure, the fingers 56 will progressively engage the bag top and will be differentially flexed 20 whereby all of said fingers may ultimately be pressed into engagement therewith. In each of Figs. 4 and 5 a true level is indicated by the line L. It will be understood that the showing in these figures is exaggerated and is presented merely for illustration.

25 It will be apparent from the above description that there is provided a structure which attains the objects of the invention. While for purposes of compliance with the patent statutes a detailed description of such structure has been made, it is obvious that modifications and variations may be resorted to by those skilled in the art and it is, therefore, to be understood that such description shall be taken in an illustrative rather than in a limiting sense and that the scope of the invention shall be limited only by the appended claims.

I claim:

30 1. In a machine for closing filled bags; a row of adhesive carrying fingers and means to press said fingers against the surface of a filled bag whereby to apply spaced relatively narrow stripes of adhesive to such surface, said fingers being flexible and resilient whereby to permit the several fingers to conform to any irregularities of such surface; and means to form a closure by folding a portion of said bag into contact with said surface.

35 2. In a machine for closing filled bags; a row of adhesive carrying fingers and means to press said fingers against the surface of a filled bag whereby to apply spaced, relatively narrow stripes of adhesive to such surface, said fingers being flexible and resilient whereby to permit the several fingers to conform to any irregularities of such surface; means to cause relative movement between said fingers and said surface while said fingers are pressed thereagainst for spreading the adhesive thus applied; and means to form a closure by folding a portion of said bag into contact with said surface.

40 3. In a device for applying adhesive to irregular surfaces of filled bags, a series of aligned fingers adapted to carry adhesive to and to make contact with such surfaces, said fingers being

flexible and resilient whereby to permit the several fingers to conform to the irregularities of said surfaces.

4. A device for applying spaced, relatively narrow stripes of adhesive to irregular surfaces of filled bags and comprising an aligned series of spaced relatively narrow fingers adapted to carry adhesive to and be pressed into contact with such surfaces, each of said fingers being flexible and resilient whereby the several fingers may conform to the irregularities of such surfaces when pressed thereagainst.

5. In a device for applying adhesive to irregular surfaces of filled bags; a series of aligned fingers adapted to carry adhesive to and to make contact with such surfaces, said fingers being flexible and resilient whereby to permit the several fingers to conform to the irregularities of said surfaces; and means effective to move said fingers through a predetermined path of travel whereby the applied adhesive will be evenly spread.

6. A device for applying spaced, relatively narrow stripes of adhesive to irregular surfaces of filled bags comprising an aligned series of spaced, relatively narrow fingers adapted to carry adhesive to and be pressed into contact with such surfaces, each of said fingers being flexible and resilient whereby the several fingers may conform to the irregularities of such surfaces when pressed thereagainst; and means effective to move said fingers through a predetermined path of travel whereby the applied adhesive will be evenly spread.

7. In a machine for closing filled bags having the side walls of the unfilled, upwardly extending mouth portion tucked inwardly and having the front and rear walls thereof collapsed upon the top of the contents and upon said inwardly tucked side walls to form a flattened upwardly extending mouth: a source of adhesive; means to

10 transfer adhesive from said source to a portion of the bag overlying the top of the contents thereof, said means comprising a flexible resilient plate having a plurality of spaced slots extending inwardly from one edge thereof to form adhesive-carrying fingers whose extremities are defined by said edge; means to move said fingers from said source of adhesive into operative position relative to said bag; means to press said fingers upon the top of the bag with the extremities thereof lying at the apex of the angle between the top of the bag contents and the upwardly extending collapsed mouth; means to initiate folding of said mouth along the line established by said finger extremities; means to move said fingers across the top of said bag while said fingers continue to press thereagainst whereby to cause each of said fingers to apply adhesive to a portion of said bag top; and means to complete the folding of said bag mouth and to press the same into contact with the adhesive applied by said fingers to form a closure.

15 8. In a machine for closing filled bags, means conformable to a surface of a filled bag for applying spaced, relatively narrow stripes of adhesive thereto, means to cause relative movement between said adhesive-applying means and said surface for spreading the adhesive thus applied, and means to form a closure by folding a portion of said bag into contact with said surface.

20 9. In a machine for closing filled bags, means conformable to a surface of a filled bag for applying spaced, relatively narrow stripes of adhesive thereto and comprising a row of adhesive-carrying fingers; means effective to move said fingers through a predetermined path of travel whereby the applied adhesive will be evenly spread, and means to form a closure by folding a portion of said bag into contact with said surface.

MARCEL A. NICOLAS.
